WINDOW

Anthony G. Lemos, Plainfield, N. J.

Application March 26, 1949, Serial No. 83,549

5 Claims. (Cl. 20—42)

1

This invention relates to improvements in windows. In particular, the invention is directed to an assembly of movable window sash of the kind used in the construction of dwellings or the like to both admit light and to adjustably provide for ventilation. Additionally, my invention comprehends component parts for a window assembly by which supplementary sash may be removably installed therewith to create dead air space at glazed areas and a resulting decrease in the rate of heat transmission through the window.

My invention has for its principal object the provision of a window assembly giving adequate lighting which may be opened or closed in a manner which provides efficient and well regulated ventilation. It is a further object of my invention to provide an assembly of several movable window sash which, when in closed position, are firmly sealed with respect to one another and with respect to all mating surfaces in the window frame. A further object of my invention is to provide a window assembly adapted to double glazing, or to which supplementary sash may be quickly and easily added to form a dual-pane window. A still further object of my invention is to provide a movable window sash assembly, the component parts of which may be easily manipulated and readily cleaned, and one which presents a pleasing appearance and useful combination for the transmission of light and air.

These and other important objects and advantages of my invention are attained, in part, by the use of a three sash unit which differs substantially from the conventional two sash sliding window assembly. Two upper sash elements are slidably disposed in a window frame and are counterbalanced with each other, and the third and lowermost sash is pivotably swung from the window frame adjacent the lower reaches thereof. Conveniently manipulated hardware is installed in the sash elements and window frame whereby the lowermost or pivoting sash may be latched against the lower of the two sliding sash when the window is closed, and at the same time the lowermost pivoting sash is secured against pivoting with respect to the window frame. Clamping action thus obtained is distributed in a novel fashion to effect a tight hermetic seal at mating surfaces between the sash elements and to also create tight joints between the sliding sash elements and the pulley stiles in the window frame, thus avoiding a necessity for auxiliary weatherstripping at these joints.

2

The invention will best be understood by a consideration of the following detailed description of a preferred physical embodiment of the invention taken in conjunction with the annexed drawings. It will be understood that the preferred embodiment described herein is illustrative only and that various changes may be made in the size, shape, and the arrangement of parts used in the construction of my window assembly which are within the scope of the invention as particularly pointed out in the subjoined claims.

In the drawings,

Figure 1 is a front elevation view of a window assembly which incorporates the features of my invention, taken from the inner side of the window,

Figure 2 is a vertical cross-section view taken through the window assembly of Figure 1 on lines 2—2,

Figure 3 is an enlarged vertical cross-section view of the window assembly of Figure 1, partly fragmentary and foreshortened to fit within the confines of the page,

Figure 4 is a fragmentary vertical cross-section view taken on line 4—4 of Figure 1 to illustrate clamping hardware,

Figure 4a is a fragmentary enlarged view of the clamping hardware of Figure 4,

Figure 5 is a horizontal fragmentary cross-section view illustrating a sash pivot,

Figure 6 is a fragmentary vertical cross-section taken on line 6—6 of Figure 1 showing clamping hardware recessed in the vertical window frame,

Figure 7 is a fragmentary vertical cross-section view showing supplementary pane attachment, taken on line 7—7 of Figure 1,

Figure 8 is a fragmentary vertical cross-section view on line 8—8 of Figure 1 to illustrate the window lift on the lower sliding pane, and

Figures 9 and 10 are fragmentary cross-sectional views of dual window sash of alternative structure which may be employed in the window assembly of my invention.

Referring to the drawings, in Figures 1 and 2, the window assembly is outlined by a window frame 11 constructed of vertical and horizontal component members with suitable trim and sill structure. I prefer to employ wood in so constructing the frame and window sash structural members to be later described, although wood substitutes may be used as desired. Confined within the frame are glazed upper and lower

vertically sliding window sash 12, 13 respectively and a pivoting lowermost window sash 14. The lowermost sash 14 is pivoted for inward tilting to a pair of opposite window hangers 20, as at 21, and may also be swung clear of the window frame on the hangers 20 at pivots 22 secured to the window frame. The pivoting connections 21 see also Figure 5, are preferably such as to present a degree of frictional engagement whereby the window itself will remain substantially in any set position when it is opened. If desired, for large and heavy window sash, the pivoting point 21 may be located closer to the mid-point of the sides of the lowermost sash 14 so that, in addition to a nominal frictional engagement, the sash will be balanced.

Sliding sash 12 and 13 are counterbalanced with each other by the use of a pair of flexible supporting cables 25 affixed to the sash in suitable recesses located in their side structure near their top edges, cables 25 being trained upwardly from each sash and over rotatable pulleys 26 mounted in window frame 11. Customary stops and separating strips in the window frame confine the sliding sash 12 and 13 for vertical movement only, and when lower sash 13 is lifted as, for example, to the dotted line position of Figure 2, the upper sash 12 lowers to a corresponding position with respect to the vertical dimensions of the window frame.

Referring to Figure 3, the lowermost sash 14 may be pivoted angularly inwardly or it may be swung clear of frame 11 down into position against the sill of frame 11, as illustrated in the two broken line positions; or it may be closed completely as shown in full, whereupon the lower structural member abuts the window sill, and a recess 28 in its lower edge engages weather-stripping 29 on the lower horizontal frame member to provide a seal against the transmission of air or drafts. Swinging movement on pivots 22 is restrained in favor of pivoting by the use of tension springs 23 interposed between hangers 20 and frame 11. The lower corners of the sash section are given a slight radius and are faced with a pair of curved abutment plates 30 which bear against the vertical parting strips or beads 31 during closure to avoid excessive wear which would otherwise occur as the relatively soft wood of the sash frame engages the relatively hardwood bead. On its upper edge, sash 14 is inclined downwardly outwardly and is notched as at 32 in order to present adequate vertical bearing against a corresponding notch 32' in sash 13. Side strips 33 affixed to sash 14 form a closure at the window frame and correspond as a continuation with the vertical front stops 34 which guide the inner side of sliding sash 13.

The upper horizontal structural member or check rail of sliding sash 13 has an outwardly extending ledge 35 coextensive between parting beads 31, more clearly seen in Figure 7, from which depends a downwardly inclined hook-shaped face 36 to engage a corresponding upwardly inclined face 36' on inward ledge 35' on the lower structural member or check rail of the co-acting sliding sash 12. Thus, when sash 13 is pulled downwardly, which action, in turn, tends to move sash 12 upwardly, an effective draft seal is effected by reason of the wedging action produced which seals the mating edges and forces sash 13 outwardly and draws sash 12 inwardly against parting strip 31. Sufficient clearance is provided between the co-acting ledges 35 and 35' 75

and between the ledges and sash structure so that no locking action or interference takes place at these surfaces, and for the purpose of filling the clearance space between ledge 35' and sash 13, I use a spring closure strip 37 co-extensive across the sash. Corresponding with the construction of the lowermost pivoting sash, the upper sliding sash is provided with a notch 28' for its full width across the top surface which engages with a weatherstrip 29' fixed horizontally to frame 11.

A pair of clamp handles 40, see Figures 1, 4, and 4a, are mounted in brackets 41 recessed in the upper corners of pivoting sash 14, and handles 40 may be moved 90° from a horizontal open window position shown in broken lines of Figure 4a to the vertical clamping position shown in the full lines in the several views. When turned vertically, clamp handles 40 serve to rotate the right hand and left hand extending plates 42, the hook shaped portions 43 of which will engage the rotatable draw-down pins 44 trunnioned in brackets 45 in the lower sliding sash 13. The extending portion 46 of plates 42, at the same time, will enter the apertures 47 in the side plates 48, see Figure 6, recessed in frame 11 to lock sash 14 against pivoting. It will be noted at this point that aperture 47 has inclined sides whereby plate 42 may be urged in the direction of sash closure as it reaches full engagement to tightly engage the upper structure of lowermost sash 14 against the lower mating edge of lower sash 13 and against parting bead 31.

Reconsidering the aforementioned clamping and locking action as it affects the window assembly as a whole, the manipulating of clamps 40 to clamping position will (a) draw sliding sash 13 down against pivoting sash 14 and simultaneously (b) press the top edge of sash 14 outwardly of the window against the lower edge of sash 13. Pull-down action (a) will in turn, tend to increase the mutual engagement of inclined surfaces 36, 36' on the check rails which will result in further tendency for sliding sash 13 to be urged into draft sealing contact outwardly of the window against strip 31 and for sash 12 to be urged inwardly against the strip. These combined actions will provide efficient weather sealing between the sash and frame and will also ensure tight sealing between the sash to preclude any necessity for auxiliary weatherstripping at these joints. The only surface contacts not so urged to closed position will be the single mating of the lowermost sash and the frame, and that of uppermost sash 12 and the frame, and at both of these locations I provide auxiliary weatherstrips.

To form a dual pane window, identical auxiliary sash elements 50 may be removably inserted in each main sash 12, 13 and 14 as shown installed in Figure 1. Each auxiliary sash 50 consists of an outlining metallic frame 51 carrying a pane 52 of glass or the like 52 and arranged to be inserted within a suitable rabbet in the structural borders of the main sash, spaced from the glazed areas thereof. Outline frame 51 has an irregular cross-sectional shape, see Figures 5, 7, and 8, including an inner peripheral notch 53 to accommodate the glass pane 52 and an adjoining outer stepped peripheral notch 54 serving to carry an insulating weather strip 55 bearing against the framework of the sash with which it is installed. A flat inner facing 56 on outlining frame 51 rests on the inside edge of the main sash elements adjacent rabbet 57 bordering the inner edge of the sash.

I prefer to removably secure auxiliary sash 50

to the main sash by hooking the outlining frames 51 over triangular points 60 or the like which are set in the lower horizontal structural members of the sash, see Figures 1 and 7, in a manner whereby the broad top edges of the points engage the step on notch 54, thus avoiding interference with weather strip 55, and by then latching the upper edge against the step on notch 54 by the use of pivoting levers 61 set in the sash framework and operative by means of the angular manipulating edges 62 recessed in the sash frame. To facilitate lifting the edges 62, I cut a small radius clearance 63 in the main sash structure whereby the auxiliary sash are readily removable for cleaning or storage.

To raise sash 13 I provide a pull member 65 recessed in the sash frame, see Figure 8, which may also serve as a catch for an additional locking clamp 66 swivelably mounted on sash 14. The additional locking provision is especially useful on long sash where the distance between the side locking clamps 40 is great and where additional stability is desired. In this respect it will be understood that for long window sections or for ornamental purposes it may be desirable to subdivide one or more of the sash into smaller sections by the use of appropriate substructure. Inasmuch as the window assembly of my invention is particularly adaptable to large window areas or picture windows, it may further be desirable to employ metal counterbalancing pulley hangers to more adequately carry the load which exists by the use of large areas of plate glass, rather than to merely support the pulleys 26 on simple screw-type axles as indicated in Figures 1 and 2.

Alternative windows of the fixed dual-pane type may be used with my window construction as shown in Figures 9 and 10 thus obviating the use of supplementary sash as hereinbefore described. Figure 9 illustrates a lighter type of dual pane 67 held separate and engaged by the sheet metal members 69, 70 encased in a putty-like material 71 supported in a sash frame 68. Likewise, heavier dual panes 67', as shown in Figure 10, may be mounted in sash frame 68' by the use of members 69', 70' embedded in material 71' and held securely in place by the use of moulding strips 71".

In use, the window assembly of my invention provides an efficient use of the window area for lighting and ventilation. By using three sash elements, a wider window may be constructed for broad visibility without resorting to interrupting mullions necessitated by a plurality of adjacent sliding two-sash assemblies. When cleaning the glazed areas, the lowermost sash may be swung clear of the window frame for accessibility. The lower sliding sash may be easily reached at this point and, to clean the upper sliding sash, the lower sliding sash may be elevated to a suitable position thus lowering the sash to a position of ready access.

For ventilating through the window, various degrees of window opening may be adjustably had, and desirable deflection of air may be produced by tilting action of the lowermost sash. For a limited transmission of air, the pivoting sash may be used alone or the sliding sash may be opened slightly at the top and bottom, or a combination of the two may be made. The obvious advantages gained by tilting the lower sash are the avoidance of direct drafts and also the upward deflection of air currents tending to introduce smaller quantities of floating dust and

dust suspended in the air and yet give a change of air.

To remove the sash from the frame it is only necessary to disconnect lowermost pivoting sash 14 from its hangers and remove it entirely from the window frame; and to then disengage cable 25 from pulley 26 permitting both sliding sash to be lowered to the position of the lowermost sash, whereupon the inner of the two sliding sash may be taken from the frame and the cable disconnected. The parting bead 31 is constructed in two sections, the lower section being removable from frame 41, thus making it possible to then withdraw sash 12 inwardly from the blind stops at the lower sash opening. During installation the reverse procedure is employed.

The window of my invention finds a particularly useful purpose in its use for schools and public or office buildings where adequate and improved ventilation is a problem, and where lighting is of paramount importance. At full open position there will be substantially two-thirds of the window area available for ventilation. The use of wide window areas without interrupting mullions affords generous vision and at the same time reduces the costs of windows compared with the conventional two-sash assembly. Added to these advantages are the provisions for tight sealing without extensive weather stripping and for dual pane installations of varying characteristics as well as the complete accessibility for manipulating and cleaning the sash elements.

I claim:

1. A window assembly of the class described comprising, in combination, a window frame, a pair of interconnected sliding sash superimposed in adjacent planes in the upper two thirds portion of said frame and adapted to be vertically moved to open and closed positions, a pivoting sash arranged in the lower one third portion of said frame and adapted to pivot inwardly of the frame and to close in contact with the window sill and an adjacent sliding sash, and sash clamps interconnecting said pivoting sash with said adjacent sliding sash and adapted to urge both of said interconnected sliding sash into closed position.

2. A window assembly of the class described comprising, in combination, a window frame, a pair of interconnected sliding sash superimposed in adjacent planes in the upper two thirds portion of said frame and adapted to be vertically moved to open and closed positions, a pivoting sash arranged in the lower one third portion of said frame and adapted to pivot and swing inwardly of the frame and to close in contact with the window sill and an adjacent sliding sash, and sash clamps interconnecting said pivoting sash with said adjacent sliding sash and adapted to urge both of said interconnected sliding sash into closed position.

3. A window assembly of the class described comprising, in combination, a window frame, a pair of interconnected sliding sash arranged in adjacent planes in the upper two thirds portion of said frame and adapted to be vertically moved to open and closed positions, a pivoting sash arranged in the lower one third portion of said frame and adapted to pivot inwardly of the frame and to close in contact with the window sill and an adjacent sliding sash, and sash clamps interconnecting said pivoting sash with said adjacent sliding sash adapted to urge said pivoting sash into mutual contact with said adjacent sliding sash and to simultaneously urge both of said

interconnected sliding sash into closed position.

4. A window assembly of the class described comprising, in combination, a window frame, a pair of interconnected sliding sash disposed in adjacent planes in the upper two thirds portion of said frame and adapted to be moved to open and closed positions, vertical stops in said frame to guide the sliding sash, a pivoting sash arranged in the lower one third portion of said frame and adapted to close in contact with the window sill and an adjacent sliding sash, and sash clamps interconnecting said pivoting sash with said adjacent sliding sash adapted to urge the sliding sash vertically into closed position and horizontally with respect to said vertical stops into sealing engagement therewith.

5. A window assembly of the class described comprising, in combination, a window frame, a pair of interconnected sliding sash disposed in adjacent planes in the upper two thirds portion of said frame and adapted to be moved vertically to open and closed positions, vertical stops in said window frame to guide the sliding sash, interengaging edges on the check rails of the sliding sash to urge said sash horizontally toward each other against said vertical stops when in closed position, a pivoting sash arranged in the lower one third portion of said frame adapted to

close in contact with the window sill and an adjacent sliding sash, and sash clamps interconnecting said pivoting sash with said adjacent sliding sash and with said frame and adapted to urge said adjacent sliding sash vertically with respect to said window frame to closed position and horizontally with respect to said vertical stops.

ANTHONY G. LEMOS.
